UNITED STATES PATENT OFFICE.

JAMES PICKEN, OF PORT WILLIAM, SCOTLAND, ASSIGNOR OF ONE-HALF
TO ARTHUR ALLAN, JR., OF GLASGOW, SCOTLAND.

PNEUMATIC GUN OR RIFLE.

No. 836,532.

Specification of Letters Patent.

Patented Nov. 20, 1906.

Application filed December 30, 1902. Serial No. 137,115.

To all whom it may concern:

Be it known that I, JAMES PICKEN, retired farmer, a subject of the King of the United Kingdom of Great Britain and Ireland, and 5 a resident of Port William, in the county of Wigton, Scotland, have invented an Improved Pneumatic Gun or Rifle Particularly Applicable for Military Practice, of which the following is a specification.

10 This invention relates to fluid-operated guns or rifles; and its object is to increase the amount of pressure supplied behind the projectile.

15 Other objects and advantages of this invention will appear from the following description and be more particularly pointed out in the annexed claims.

20 In the accompanying drawings, Figure 1 is a side view of a portion of the improved gun. Fig. 2 is an elevation, partly in section, showing the condition of the parts when ready for firing. Fig. 3 is a view similar to Fig. 2, showing the condition of the parts after firing. Fig. 4 is an elevation, partly in 25 section, showing the gun broken down as in the act of returning to firing position, the pistons being in their operative positions. Fig. 5 is a transverse section of the cylinder A and a plan through the lug a' . Fig. 6 is a section 30 of the cylinder A, showing the piston a and engagement of the lug a' and sliding block g . Fig. 7 is an elevation, partly in section, showing the gun broken in the act of pressing the pistons to their operative positions, the 35 toggle-levers being in engagement with the pistons.

The gun herein shown and described is of the "breech-loading" type; but I desire it to be understood that I do not wish to be limited to this particular type of gun.

40 In this embodiment of my invention the stock D is hinged to the barrel C at f , and each is provided with one or more cylinders A B, in which work pistons or compression-heads a b . The piston of the barrel A moves upon firing toward the barrel C, so that the piston a moves in opposite directions, thereby by moving the fluid in the opposite direction.

45 The chambers of the several cylinders communicate by channels 1 2 with the barrel C. The pistons or compression-heads a b are hollow and open at one end. Spiral springs j are inserted at one end into the open ends of the pistons a b , the other ends of the springs

55 bearing against the non-compression ends of the cylinders A B. Lugs a' project downwardly from the pistons a b and are guided in suitable slots in the bottom of the cylinders A B. g represents sliding blocks also moving in the slots of the bottom of the cylinder A B and are provided with flanges g' , which fit into channels or grooves a^2 a^3 in the walls of the slot. The blocks g are pivoted to compression toggle-levers G H. Each of these levers is fulcrumed to a part of the gun 60 other than that which it is to operate—*i. e.*, the lever G is fulcrumed at e to the housing F of the stop B, while the lever H is fulcrumed at e' to the housing E of the barrel C.

When it is desired to load, the gun is 70 broken, the stock and the barrel moving upon the housing G, thus moving the pistons a b through the medium of the toggle-levers G H. As the block g is pivoted to the levers G H, it will be seen that when the gun is 75 broken for loading the lever G will be moved toward the front end of the barrel while the lever H is moved toward the stock, thus moving the block g , which engages the lug a' on the cylinder a and compresses springs j . 80 At the same time dogs m n in the housing E F pass into notches a^4 and b^2 and hold the pistons a b in a position for firing. These dogs m n are connected at m^2 m^3 with slide-bolts p q , passing through stop-plates p^2 q^2 , 85 and which normally tend to throw said dogs into engagement with the pistons a b by reason of spiral springs p' q' , which force the bolts p q toward each other and which bear against the stop-plates p^2 q^2 . When the 90 slide-bolts p q move the dogs m n into engagement with the pistons a b , the pawls u x , pivoted at u' x' and pressed by springs u^2 x^2 , enter notches r' t' in the slide-bolts and hold said slide-bolts against movement, so 95 that the greater power of springs j cannot overcome the lesser power of the springs p' q' when the breech is closed. Upon the ends of the slide-bolts p q are respectively a movable pawl p^3 and a fixed pawl q^3 , which are 100 adapted for coengagement when the breech is closed.

A trigger L, pivoted at l in the housing F of the stock D, is adapted to contact when moved, first, with extensions u^3 x^3 upon, respectively, the pawls u x and throw said pawls out of engagement with the slide-bolts p q , and second, by means of an extension l' 105

with the movable pawl p^3 to release both slide-bolts p q simultaneously, and consequently both dogs m n . The barrel and stock are locked together, so that they cannot separate on firing, by a spring-dog i , carried by the stock and engaging in a notch on the barrel. (See Fig. 2.) A pivoted cam-lever k engages beneath the dog i to unlock the same.

The operation is as follows: When it is desired to fire the gun when it is in a position shown in Fig. 3, the dog i is unlocked by the compression-lever k , and the parts are swung on their hinge f , whereby the compression-levers force the pistons a b against the action of the springs j through the medium of the blocks g and lugs a' . When the notches a^4 b^2 reach the dogs m n , said dogs enter the notches, being thrown therein by the springs p' q' , which move the slide-bars p q , which are now locked by pawls u x . The projectile is now inserted into the barrel and the breech closed, whereupon the pawls p^3 q^3 engage. The trigger L is then pulled, which first throws the pawls u x out of engagement with the slide-bars p q , and then the pawl p^3 is thrown out of engagement with the pawl q^3 , whereupon the superior power of the springs j overcomes the power of the springs p' q' and the pistons move toward each other, simultaneously compressing the fluid within the chambers and forcing it by way of the channels 1 and 2 to the barrel C.

I claim—

1. In a fluid-operated gun, the combination with a barrel, separate cylinders connected with said barrel, of a plurality of pistons and means for moving the pistons si-

multaneously in opposite directions to supply fluid to said barrel at the same time.

2. In a fluid-operated gun, the combination with a barrel and a stock hinged together, of cylinders carried by the barrel and the stock and communicating continuously with the barrel, pistons in the cylinders, means moving the pistons in the cylinders and single means for releasing all of said pistons simultaneously.

3. In a fluid-operated gun, the combination of a barrel, a plurality of cylinders in continuous communication with the barrel, a plurality of pistons in said cylinders, means moving said pistons simultaneously in a direction to compress and force fluid into said barrel and toggle means for simultaneously resetting said pistons.

4. In a fluid-operated gun, the combination with two pistons, springs for moving the pistons in a direction to compress fluid, a dog for each piston holding it against movement, two slide-bars, one provided with a fixed pawl and the other with a movable pawl, means for moving the movable pawl to release both pistons simultaneously.

5. In a fluid-operated gun, the combination of a barrel, a stock hinged thereto, a piston carried by each, a plurality of cylinders in which said pistons operate and compression-levers connected with each piston and to said barrel and to said stock.

JAMES PICKEN.
